UNITED STATES PATENT OFFICE.

ANDREW E. RIDDERSTROM, OF NAHANT, MASSACHUSETTS, ASSIGNOR, BY MESNE ASSIGNMENTS, TO THOMAS C. ROWEN, OF SWAMPSCOTT, MASSACHUSETTS.

TOOL HOLDER.

Application filed May 6, 1920. Serial No. 379,250.

To all whom it may concern:

Be it known that I, ANDREW ROBERT RIDDERSTROM, a citizen of the United States, and resident of Nahant, in the county of 5 Essex and Commonwealth of Massachusetts, have invented a new and useful Improvement in Tool Holders, of which the following is a specification.

The present invention relates to tool 10 holders, and more particularly to rotatable holders for the buffing heads of buffing or polishing machines, such as are used to buff or polish the shanks of shoe soles during the manufacture of shoes.

15 When the sand paper or other abrasive that is mounted upon the buffing head becomes worn through use, the buffing head is removed, the worn sand paper is replaced by a fresh sheet, and the head is then re- 20 turned to its holder. During the removal of the buffing head from, and its return to, the holder, it has been customary hitherto either to stop the machine altogether by disconnecting it from its source of power, or 25 to hold the tool holder and its driving shaft stationary while the driving belt was permitted to slip over the driving pulley keyed to the driving shaft. As it is necessary to replace the worn sand paper at fre- 30 quent intervals, both of these methods involve the loss of considerable valuable time and the latter method is further objectionable because subjecting the machinery to unnecessary and undesirable wear and tear.

35 An object of the present invention, accordingly, is to provide a tool holder of the above-designated character that shall be adapted to permit the removal of the tool, and its replacement, during the rotation of 40 the tool holder and without necessitating stopping the machine or subjecting it to unnecessary wear.

With this object in view, a feature of the invention resides in an improved tool holder 45 that is provided with separable jaws that may be readily separated during the operation of the machine to permit the removal of the tool. The jaws are normally maintained in effective position, and are prefer- 50 ably screw threaded, so that the correspondingly screw-threaded stem of a tool may be readily inserted between, and automatically clutched by the jaws. Owing to the action of the screw threads, furthermore, the 55 parts of the tool are tightened together

when clutched, causing the sand paper or other abrasive to be firmly clamped in position.

A further object of the invention is to simplify and improve upon tool holders of 60 the class herein considered, rendering them simpler and more rugged in construction, cheaper to manufacture and more effective and reliable in operation.

With these ends in view, the invention 65 consists of the improved tool holder herein-after described, illustrated in the accompanying drawings, and defined in the appended claims.

In the drawings, illustrating a preferred 70 embodiment of the present invention, Fig. 1 is a side elevation, showing the operative portion of a buffing machine having the present invention embodied therein; Fig. 2 is a central vertical sectional view; and 75 Figs. 3, 4 and 5 are sectional views, taken upon the lines 3—3, 4—4 and 5—5 respectively, of Fig. 2.

The rotatable tool holder of the present invention comprises two vertically disposed, so 80 relatively movable jaws 2 that are normally maintained in their effective positions, as indicated in the drawings, to clutch the stem 4 of a tool. Upon the jaws being momentarily separated, the tool will drop 85 out from between them. The removal of the tool may thus be easily and readily effected during the rotation of the tool holder. The tool may be as easily and readily reclutched while the tool holder is rotating. To this end, the jaws are adapted 90 to be returned to effective positions immediately upon the release of the momentary jaw-separating means, and, in the specific embodiment of the invention that is herein 95 illustrated and described, they are provided with screw threads 5 and the tool stem 4 is similarly threaded at 6. Upon the threaded end of the stem being positioned at the lower ends of the jaws, therefore, the 100 rotation of the tool holder will automatically cause the tool stem to be drawn gradually into position between the jaws, which will then clutch the tool as firmly as before.

105 The mechanism whereby the jaws are normally maintained in effective position, and whereby they may be momentarily separated, will now be described. The jaws are mounted within an intermediate, longitu-

dinal, diametrical slot 8 in the lower enlarged head 10 of a vertically disposed driving shaft 12 that is mounted to rotate in bearings 14 and 16 of a frame or support 18. 5 The slot 8 extends nearly throughout the length of the enlarged head 10, but not through the lower end thereof. The jaws are intermediately pivoted upon a pin 20 that is diametrically screwed into, or otherwise secured to, the shaft, at right angles to the plane of the slot 8. The tail ends 22 of the jaws are respectively adapted to be engaged by oppositely disposed cams 24 provided upon the upper interior wall of a vertically disposed, cylindrical sleeve 26 that encloses the greater part of the enlarged head 10 and the jaws mounted thereon. The head of the pin 20 is positioned within a slot 28 that extends transversely across 10 the sleeve through a quarter circumference of the cylinder. The rotative movement of the sleeve relatively to the shaft is thus limited to ninety degrees. The head of the pin serves also partly to support the sleeve 15 upon the shaft head.

When one end wall 30 of the slot engages the head of the pin, at one of the limits of rotative movement of the sleeve, the cams 24 are positioned ninety degrees away from 20 the tail ends 22 of the jaws, so that the tail ends are permitted to separate and the jaws to close in towards each other into effective position, as illustrated. The agency for thus closing the jaws in towards each other 25 comprises oppositely disposed cams 32 interiorly provided upon the lower wall of the sleeve and acting directly, one upon each jaw end of the jaws. The cams 32 are angularly ninety degrees removed from the cams 24, so as to permit their acting upon 30 the jaw ends of the jaws at a time when the tail ends are free from the restraining influence of the cams 24. Conversely, by this construction, the cams 24 will be adapted 35 to act upon the tail ends of the jaws when the jaw ends are out of contact with the cams 32. The slot 28 is positioned angularly midway between adjacent cams of the pairs of cams 24 and 32. When the other 40 wall 34 of the slot 28 engages the head of the pin 20, at the other limit of rotative movement of the sleeve, therefore, the cams 24 will act upon the tail ends 22 to effect the opening of the jaws. By a simple, 45 ninety-degree rotation of the sleeve 26 relatively to the shaft, therefore, the jaws may be readily separated and, by a reverse rotation, as readily returned to effective clutching position. The specific actuating mechanism 50 for the jaws that has been hereinbefore described is not claimed herein, the invention residing not in structural details and mechanical movements, but in the combination of elements whereby the purpose of 55 the invention is attained.

The driving shaft 12, with the tool holder mounted thereon, is adapted to be rotated in its bearings by a belt passing over a driving pulley 36 that is fixed to the driving shaft in any desired manner. To remove 70 the tool from the tool holder, it is not necessary either to stop the machine or to hold the driving shaft stationary while the belt is permitted to slip over the pulley, as has been the custom heretofore. All that is 75 necessary is to touch the sleeve 26 lightly for a moment with the hand to retard its rotation relatively to that of the driving shaft. During the moment that the sleeve is thus held against full rotation with the 80 shaft, the shaft, continuing to rotate, and the jaws that are pivoted thereon rotating therewith, the cams 24 of the relatively stationary sleeve will engage the tail ends of the jaws, causing the jaw ends to separate, 85 and permitting the tool to drop out from between them by gravity.

The jaws should be immediately returned to their effective positions so as to be in readiness to reclutch the tool. To bring 90 this about, the sleeve, according to the present embodiment of the invention, is yieldingly maintained in the illustrated, jaw-closing position, so as to be immediately returned thereto when the operator, after 95 touching it lightly to effect a separation of the jaws, as above described, removes his hand. One end 38 of a spring 40 that is coiled about the shaft is secured thereto and the other end 42 is mounted within any one 100 of a plurality of slots 44 provided upon the upper end of the sleeve. The spring acts to maintain the tool holder yieldingly in the normal, illustrated position. The tension of the spring acting yieldingly to return the 105 tool holder to its normal, effective position may be adjusted by mounting the end 42 of the spring in one or another of the slots 44.

The tool holder of the present invention is thus adapted to occupy two positions in one of which, its normal position, it is effective to clutch a tool and in the other of which it is ineffective. The tool holder is yieldingly maintained in its normal position so as to be in readiness to reclutch the tool. 110

The tool illustrated in the drawings is a buffing head of separable parts comprising, in addition to the threaded stem 4, a conically recessed, flanged hub 46 freely centrally mounted thereon, a felt disk 48 glued or otherwise secured to the hub, and a sheet 50 of sand paper or other abrasive loosely interposed between the disk and the head of the stem 4. The lower end 51 of the shaft head 10 is conically tapered so as to fit snugly within the conical recess of the hub 46 and is axially bored at 53 to receive the stem 4 and guide it to the jaws 2. The same act which automatically draws the tool inwardly into position upon the tool holder, there- 115 120 125 130

fore, during the rotation of the shaft, causes the hub to become securely positioned upon the end of the shaft and serves to clamp the sand-paper sheet 50 tightly in place between the head of the stem and the felt pad.

To further the clamping action, the head of the stem is enlarged, as shown at 52.

The invention is not limited to the specific embodiment thereof that is herein illustrated and described, but may be modified within the skill of the artisan without departing from its spirit and scope as defined in the appended claims.

What is claimed is:

15. 1. In combination, a rotatable tool holder having relatively movable, screw-threaded jaws adapted to occupy a normal position when not clutching a tool and a stop separated from the jaws, a tool comprising a screw-threaded stem provided with a terminal head, a hub and a disk loosely and slidably mounted on the stem, and a sandpaper sheet interposed between the disk and the head, and means for rotating the tool holder 20 to cause the stem to be threaded into position between the jaws when the jaws occupy the normal position during the rotation of the tool holder to cause the stop to engage the hub tightly and to cause the sandpaper sheet to become tightly clamped between the disk and the head, and means for separating the jaws to release the tool during the rotation of the tool holder, whereby disassociation of the tool parts is expedited by 25 facilitating detachability from the tool holder.
2. In combination, a rotatable tool holder having relatively movable, screw-threaded jaws adapted to occupy a normal position 30 when not clutching a tool and a stop separated from the jaws, a tool comprising a screw-threaded stem provided with a terminal head, a hub and a disk loosely and slidably mounted on the stem, and a sandpaper sheet interposed between the disk and the head, means for rotating the tool holder to cause the stem to be threaded into position 35 between the jaws when the jaws occupy the normal position during the rotation of the tool holder to cause the stop to engage the

hub tightly and to cause the sandpaper sheet to become tightly clamped between the disk and the head, the tool holder having a cylindrical sleeve adapted to be rotated with respect to the tool holder and having two pairs of interior, oppositely disposed cams, the cams of one pair being adapted to engage the jaws to effect a relative movement of the jaws into the normal position, and means for normally maintaining the sleeve in a position relatively to the tool holder such that the jaws are maintained by the cams of the said one pair in the normal positions, the cams of the other pair being adapted to engage the jaws to separate them, and the sleeve being adapted to be actuated during the rotation of the tool holder to cause the cams of the second-named pair to separate the jaws to release the tool, whereby disassociation of the tool parts is expedited by facilitating detachability from the tool holder.

3. A tool holder having a cylindrical sleeve provided with a transverse slot extending over a quarter circumference of the cylinder and with two pairs of interior, oppositely disposed cams, the cams of each pair being removed ninety degrees from the cams of the other pair and the slot being positioned angularly midway between adjacent cams of the different pairs, a pin mounted in the holder having a head extending into the slot of the sleeve, two jaws intermediate pivoted within the sleeve about the pin, and means for maintaining an end wall of the slot in engagement with the head of the pin, one pair of the cams then engaging the jaw ends of the jaws to maintain the jaws in effective position, the sleeve being adapted to be rotated so as to cause the other end wall of the slot to engage the head of the pin, the other pair of cams then engaging the tail ends of the jaws to effect the opening of the jaws and to permit the ready removal of the tool.

In testimony whereof, I have hereunto subscribed my name this 30th day of April, 1920.

ANDREW R. RIDDERSTROM.
